STORAGE AND DISPLAY STAND

Joseph A. Winger, Houston, Tex.

Application December 30, 1950, Serial No. 203,636

4 Claims. (Cl. 312—215)

1

This invention relates to a storage and display cabinet especially adapted for the storage and display of canned oil at an automobile service station.

At automobile service stations, it is desirable and advantageous to maintain a supply of cans of oil in the various weights normally required at a conveniently accessible position close to the gasoline dispensing pumps of the station, and to display such oil prominently within the view of the station customers. The provision and handling of such a supply in an attractive display has long presented a troublesome problem. Frequently, cans of oil are stacked on window sills or ledges, and various racks have been proposed and used. In such cases, however, when the station is closed for the night, all such oil must be carried inside the station for safe keeping, and carried out again when the station is reopened. Ordinary storage cabinets provided with lockable doors are impractical, for the doors may obstruct and be obstructed by cars being serviced, and such cabinets provide no display facilities. Special A-shaped racks have been proposed provided with covers which can be removed during the day and replaced and locked in place when the station is closed. But such covers are cumbersome and must be stored in some out-of-the-way place during the day, and carried to and from such storage place when the station is opened and closed. In addition, provisions for disposal of empty oil cans are usually inadequate or totally lacking, and empty cans tend to accumulate about the station and to give an unsightly appearance.

It is the object of my invention to provide a storage and display cabinet in which an ample supply of canned oil in the various weights ordinarily required may be stored and which provides for the advantageous display of such cans of oil within clear sight of the station customers and within convenient reach of the station operator. It is an object of the invention to provide such a cabinet which may be fixedly mounted on the service island of a station along with the gasoline dispensing pumps thereof. It is an object of my invention to provide such a cabinet in which the displayed oil can be locked for safe keeping when the station is closed for the night.

It is an object of my invention to provide in such a cabinet movable can-receiving shelves which have a storage position permitting the cabinet to be closed and locked, and a display position which prominently displays at least the front cans on the shelves, and to provide shelves

2

of sufficient area to carry replacements for the front cans on the shelves. It is an object of the invention to provide such a cabinet in which canned oil is displayed and accessible at both sides of a service island on which it is mounted, and so to relate the shape of the cabinet and closure panels therefor that large display openings will be provided while the closure panels for such openings may be stored against adjacent walls of the cabinet in a face-out position giving a neat and pleasing appearance, permitting advertising matter on such panels to be in display position whether the panels are in cabinet closing position or in storage position. It is an object of my invention to provide in such a cabinet a convenient storage drawer for empty oil cans, as of a size adapted to receive a standard canned oil case, so that as the oil is used the cans may be immediately and conveniently disposed of by return to the case and can be finally disposed of in case lots. The cabinet also desirably contains a utility drawer, as for the convenient reception of charge books, etc.; and it is my object to provide that the closing of the can display space will secure the drawers in closed position.

A cabinet embodying my invention is desirably of generally square cross section and generally upright walls, mounted on a suitable base and covered by a suitable top, and forming one or desirably two can-storage compartments open at the front. For each compartment, I provide a closure panel which may be locked in compartment-closing position, or may be removed therefrom and hung in face-out position against a side wall of the cabinet. Within each compartment I provide a series of shelves which desirably are movable between two positions. In their rearward position, the shelves hold the oil within the storage compartment behind the closure position, while in their forward or display position, the shelves support the front cans in a display position exposed beyond the front edges of the compartment walls. Desirably the cabinet provides two such oil storage compartments, opening through opposite faces of the cabinet. In the lower portion of the cabinet I desirably provide a can-disposal drawer movable to an open position from either face of the cabinet, and of a size to receive a standard canned-oil carton. At the extreme top of the cabinet I desirably provide a shallow utility drawer, also desirably openable in both directions for ready access from either face of the cabinet. The closure panels for the oil compartments are desirably of sufficient size to overlap both the utility drawer and the can-

disposal drawer, and means are provided for locking such closure panels in compartment-closing position, where they also lock the two drawers in closed position.

In this specification, I use "canned" and "can" generically. The cabinet of my invention is particularly intended for the storage and display of products, such as oil, put up in the common cylindrical metal cans, but it is also useful for, and I intend to include, containers of other materials, as of paper, glass, etc., and containers of other shapes than cylindrical.

The accompanying drawing illustrates my invention:

In such drawing, Fig. 1 is a front elevation of a cabinet embodying my invention, with the closure panels shown in storage position; Fig. 2 is a side elevation of the cabinet with one closure panel shown in stored position against the near side of the cabinet, and with a second closure panel shown in closure position against the right-hand face of the cabinet; Fig. 3 is a horizontal section taken on the line 3—3 of Fig. 1; Fig. 4 is a vertical central section of the cabinet; Fig. 5 is a partial horizontal section taken on the line 5—5 of Fig. 4; and Fig. 6 is a partial horizontal section taken on the line 6—6 of Fig. 4.

The cabinet shown in the drawing comprises a base 10, two side walls 12, a top 14, and two closure panels 16 shown in Fig. 1 in storage position, all of formed sheet metal. The in-turned edges of each side wall 12 are connected by three angle-iron shelf supports 18, with the horizontal legs thereof extending inwardly from the bottom of the vertical legs. The two side walls are interconnected by a horizontal panel 20 which supports the bottom set of shelves and which forms the floor of the oil storage portion of the cabinet. Such floor panel 20 has up-turned side flanges 19, and is connected to narrow front panels 21 extending between the side-walls 12. A second horizontal panel 22 forms the top of that oil storage portion and a floor for the utility drawer compartment. A central transverse panel 24 extending vertically between the said two panels divides the oil storage portion of the cabinet into two oppositely-open oil-storage compartments. Conveniently the central panel is provided with notches 26 to pass the shelf supports 18.

At the bottom, the cabinet is provided with a suitable support for a slideable can-disposal drawer 30, and this is shown as a third horizontal panel 28. The can-disposal drawer 30 is conveniently of frame construction, comprising two drawer fronts 32, a bottom panel 34, and brace members 36 joining the drawer fronts 32 to the bottom 34 at the corners of the drawer. The drawer fronts close the space between the side walls 12 at the lower portions of the front and rear faces of the cabinet, below the front panel 21. Desirably each drawer front 32 is provided with a hand opening 38, closed against the entrance of rain by a cupped stamping 39.

The utility drawer 40 at the top of the cabinet slides on the horizontal panel 22 and lies between that panel and the top 14. It has a drawer front 42 at each end, desirably provided with a hand opening 44, closed against the entrance of rain by a cupped stamping 45. The two drawer fronts 42 close the space between the side walls 12 above the horizontal panel 22, and desirably the top 14 is provided with a lip 48 overhanging each drawer front 42 to prevent entrance of water into the drawer. As is best seen in Fig. 6, each side wall 48 of the utility drawer 40 is formed

to provide an elongated groove 49, and this is engaged by a pair of spring pressed detents 50 which serve to center the drawer 40 in closed position and to arrest its movement as it is opened.

On each of the shelf supports 18 and 19 in each of the oil compartments, there is a slideable shelf 54, conveniently of open wire construction. Desirably, each shelf is two cans deep and four cans wide, so that each shelf will carry eight cans, in two rows. Each shelf has an inner can-storage position, as is shown at the upper left in Fig. 4, in which its rear edge lies adjacent the central panel 24 and its front edge lies behind the position of the closure panel 16 and preferably behind the outer edges of the side walls 12. Each shelf is slideable outward to the display position shown at the upper right in Fig. 4, a distance of approximately half the diameter of a can, and in the display position, the front half of the front cans on the shelf are exposed and project forward beyond the outer edges of the side walls 12. Desirably, the forward or display positions of the shelves are fixed by suitable stops 56, conveniently formed as fingers upturned from the horizontal legs of the shelf supports 18.

There are thus two can-receiving compartments, each containing a plurality of can-receiving shelves. With four such shelves in each compartment and with eight cans on each shelf, a total of 64 quart cans of oil may be stored in the cabinet, which is ample to provide ready availability of all of the necessary weights of oil. Each can-receiving compartment is open at the front, and the two compartments open at opposite faces of the cabinet.

To close the cabinet, as at night, there is a closure panel 16 provided for each compartment opening. This is in the form of a sheet metal stamping, with inturned edges, and is of a size to overlap the side walls 12, and to overlap both the utility drawer 40 and the can-disposal drawer 30. To support the closure panel 16 in closed position, it is provided with four inwardly projecting and down-turned fingers 62 at spaced points adjacent its side edges, and these fingers 62 take into openings 64 in the front ends of the first and third shelf supports 18. Each closure panel is desirably provided with a hand opening 72, closed against rain by a cupped stamping 73. Adjacent the top of each compartment opening there is a latch keeper 66, conveniently carried by the horizontal panel 22, and adjacent the top of each closure panel 60 there is a lock 68 having a latch 70 which may be moved into locked engagement with the keeper 66.

The cabinet is desirably substantially square in plan, and the horizontal dimensions of the cabinet are so inter-related that the closure panels 16 may be mounted either in compartment-closing positions, shown in dotted lines at the top and bottom of Fig. 3, or in storage positions shown in full lines at the sides of Fig. 3. To support the closure panels 16 in storage position, the side walls 12 of the cabinet are each provided with openings 76 to pass the fingers 62, and brackets 78 are mounted behind such openings 76 to be engaged by the fingers 62 and to retain the closure panels firmly against the side walls 12.

My cabinet may be mounted at any convenient location at a service station, and it is especially adapted for mounting on the service island with the usual gasoline dispensing pumps, and can be made to harmonize in appearance with those pumps. Normally it will be fixed in position, as by bolting its base to the service island, and dis-

posed with its can-receiving compartments opening at the opposite sides of the service island.

The several shelves of the two compartments are filled with cans of oil, in any convenient arrangement of different weights of oil, and the two compartments will contain a total of 64 quarts of such canned oil. With the shelves all filled and in their extreme-outward or display positions, the front cans on each shelf will project outward from the cabinet to form a prominent display. Similar displays are provided at both sides of the island. In such displays, the cans are readily and conveniently available for use, and as one can is withdrawn from a shelf, another may be moved forward from the rear row, to maintain the prominence and attractiveness of the display.

An empty carton is desirably placed in the can-disposal drawer 30, and as each can of oil is used, the drawer is opened and the empty can is stacked in that carton and thus promptly disposed of.

As occasion arises, the shelves can be refilled and the carton of empty cans removed. Storage capacity is such, however, that this will not ordinarily need to be done during rush periods.

During use of the cabinet the closure panels 16 are positioned as shown in Figs. 1 and 3, in face-out position against the side walls 12 of the cabinet. Such panels 16 may carry advertising matter, which will be displayed when the closure panels are in this stored position.

To close the cabinet, the several shelves 54 are pushed inward to their storage positions, which carries them and their cans behind the closed position of the closure panels. The closure panels 16 are then lifted from their stored positions as shown in Fig. 1 and are moved to closed position as shown in Fig. 4. In that position they not only close the oil-receiving compartments, but overlap the utility drawer and the empty can drawer, to hold those drawers closed. The closure panels 16 may then be locked in closed position by the lock 68. Any advertising matter which the panels carry will be prominently displayed throughout the period when the cabinet is closed.

My cabinet will avoid the necessity, required with previous canned oil display racks, either of carrying the oil itself into the station when it is closed or of carrying any cumbersome cover-members into the station when the station is open.

Ready and immediate deposition of empty cans is provided for, and the cans may be returned to the cartons from which they came, and finally disposed of in carton lots.

With my cabinet, the station operator can maintain an adequate supply of all weights of canned oil within ready reach as he serves each customer, station appearance and efficiency will be improved, and an advantageous display of oil will be within the view to all customers, whether they drive to one side or the other of the service island.

I claim as my invention:

1. A storage and display cabinet for canned oil, comprising a walled casing forming a pair of oppositely-facing, open-front storage compart-

ments, removable closures for the open fronts of said compartments, means to support said closures in compartment-closing position, a series of movable shelves in each compartment, each 5 of said shelves being arranged to carry a display row of cans at the front and reserve cans behind the display cans, said shelves having a display position in which they project beyond the closure position a distance equal to approximately one-half the thickness of a can and in which the front halves of a display row of cans thereon are exposed outside said compartment and reserve cans thereon are concealed within the compartment behind the display-row of cans, stop 10 means to position said shelves in their display positions, said shelves also having a storage position in which the shelves and the cans thereon are behind said closure position, and means to store said closures against the side walls of said casing.

2. A storage and display cabinet as defined in claim 1, which is generally rectangular in shape and which has side walls of a width at least as wide as said closures, and means to support said closures in face-outward position against said side-walls.

3. A storage and display cabinet as defined in claim 1, with the addition of a disposal drawer below said storage compartments and oppositely openable in directions of opening of said compartments, said closures being arranged to overlap the ends of said drawer when in compartment-closing position, to prevent drawer opening when said compartments are closed.

4. A dispensing and display cabinet, comprising a base, a pair of generally upright side-walls, a horizontal partition dividing the space between said side walls, a disposal drawer below said partition, a central partition above said horizontal partition and forming with said side-walls a pair of oppositely-facing open-front storage compartments, supports in each compartment adapted to support items thereon in exposed display position projecting beyond the front edges of said compartments, and a removable closure panel for each compartment which in closed position overlaps said drawer, and means to lock said closure panels in compartment-closing position with their lower edges overlapping the drawer.
